UNITED STATES PATENT OFFICE.

HENRY D. B. LEFFERTS, OF NEW BRUNSWICK, NEW JERSEY, ASSIGNOR OF
ONE-HALF OF HIS RIGHT TO EDWIN GULLICK.

CLOTH-STRETCHING MACHINE.

SPECIFICATION forming part of Letters Patent No. 231,881, dated August 31, 1880.

Application filed January 10, 1880.

To all whom it may concern:

Be it known that I, HENRY D. B. LEFFERTS, of New Brunswick, in the county of Middlesex, and in the State of New Jersey, have invented certain new and useful Improvements in Cloth-Stretching Machines; and I do hereby declare that the following is a full, clear, and exact description thereof, reference being had to the accompanying drawings, and to the letters of reference marked thereon, making a part of this specification.

The nature of my invention consists in the construction and arrangement of a machine for stretching cloths and cassimeres after they have been printed and shrunken, for the purpose of bringing them back to their original length, as will be hereinafter more fully described, and set forth in the claims.

In order to enable others skilled in the art to which my invention appertains to make and use the same, I will now proceed to describe its construction and operation, referring to the annexed drawings, in which—

Figure 1 is a perspective view of my machine. Fig. 2 is a cross-section of one of the rollers.

A represents the frame of the machine, the four upright corner-posts of which are slotted vertically from their upper ends downward for a suitable distance, as shown at *xx*. The corner-posts at each end of the machine are connected by a cross-bar, B, and in the bottom of the slots *x* are placed the journals of a roller, C. Above this roller is placed another roller, C', the journals of which also project through the slots *x*, and have bearings or boxes *a* placed above them.

D is a tension-bar having its ends placed on top of the boxes *a* in the slots *x*, and a screw, E, screwed through the cross-bar holds said tension-bar down, so as to create more or less pressure of the roller C' on the roller C, as required.

F F are floor-rollers, and G a ceiling-roller, around which the cloth is passed in the manner shown in the drawings.

The rollers C and C' are all made alike, each roller being made of a wooden cylinder, *b*, covered with cloth *d*, and then an additional

covering, *h*, of rubber, which rubber covering is formed with series of spiral grooves *ee*, running from the center toward both ends, and at each end are teeth *i*. The spiral grooves draw the cloth smooth toward both edges, while the teeth take hold of the edges and carry the cloth along.

The two rollers C C' at each end of the machine are suitably geared together, and band-pulleys and bands are provided, so as to give the rollers a uniform motion when the machine is in operation.

By the application of the rubber-covered rollers I secure a perfectly even tension on the cloth, which tension may be regulated by means of the screws E. The first or pulling roller is to be screwed down until there is sufficient power, when turning, to pull the cloth over the central and through the back rollers—say, for example, the front rollers are screwed down to a pressure of one hundred pounds, while the back or tension rollers are only screwed down to fifty pounds. The machine is started, and as the cloth is drawn through the back rollers by the revolution of the front rollers the tension or stretch is perfectly the same on every thread.

Having thus fully described my invention, what I claim as new, and desire to secure by Letters Patent, is—

1. In a machine for stretching cloth, a rubber-covered roller provided with spiral grooves and with teeth at its ends, substantially as herein set forth.

2. The combination, in a machine for stretching cloth, of four spirally-grooved rubber-covered rollers—viz., two pulling-rollers in front and two holding or tension rollers back, with devices for regulating the tension—and intermediate top and bottom rollers, substantially as shown and described, and for the purposes set forth.

In testimony that I claim the foregoing I have hereunto set my hand and seal this 26th day of December, 1879.

HENRY D. B. LEFFERTS. [L. S.]
